UNITED STATES PATENT OFFICE.

CHARLES STEWART BABB, OF CHICAGO, ILLINOIS, ASSIGNOR TO THE BARBER ASPHALT COMPANY, OF PHILADELPHIA, PENNSYLVANIA, A CORPORATION OF WEST VIRGINIA.

MELTING KETTLE.

Application filed October 17, 1921, Serial No. 508,414. Renewed January 31, 1923.

10 all whom it may concern:

Be it known that I, CHARLES S. BABB, a citizen of the United States, residing in Chicago, in the county of Cook and State of Illinois, have invented certain new and useful Improvements in Melting Kettles, whereof the following is a specification, reference being had to the accompanying drawings.

10 My invention relates to melting kettles more especially for melting asphalt, pitch, tar or other similar substances or materials used in street paving or roofing.

15 Amongst the objects of my invention are to secure, in such structures, the highest possible efficiency in operation; to obviate the possibility of burning the materials in the course of the melting; to render the operation of melting continuous, i. e., without necessitating delays necessary for successive 20 recharging as in kettles heretofore existent; and in general, to secure utmost simplicity of construction, and desirability in practice under the lowest cost of manufacture.

25 In the accompanying drawings, Fig. I is a perspective view of a melting kettle conveniently embodying my invention.

Fig. II is a cross sectional view of the same; and

30 Fig. III is a longitudinal sectional elevation of the structure.

The melting kettle herein represented as typical of my invention, is rectangular in form, and, in practice, is preferably constructed of sheet metal of appropriate thickness riveted or otherwise rigidly secured together. The structure has vertical side and end walls 1, 2 and 3, 4 respectively, which jointly form an enclosure within which the melting trough designated by the numeral 5 is suspended. The enclosure serves as a fire box and is accessible through a charging opening 6 near the bottom of the front end wall 3. It is to be particularly noted that the trough 5 terminates somewhat short of the rear end wall 4 to afford a vertical interspace 7 for the passage of the products of combustion en route to a flue indicated at 8, the latter communicating with said interspace through an opening 9 in said end wall. 40 If desired, the enclosure may be provided with a bottom as suggested at 10 in Figs. II and III, and further strengthened by channelled reinforcing rails 11-11 along its sides and by angle rails 12-12 at its ends.

As best shown in Figs. I and II, the trough 5 is V shaped in cross section with its side walls 15-15 sloping at comparatively steep angles and merging into a rounded bottom 16. In this way I obtain greater heating surface area than possible with troughs 60 of semi-circular or wholly curved cross sections and certain other advantages which will be obvious from further description.

Along opposite sides said trough has co-extensive subdivisions or pockets 17-17 65 into which the solids to be melted are placed for preheating. The lower edges of the vertical partitions 18-18 by which subdivision is effected terminate short of the sloping sides of the trough so as to afford restricted openings 19-19 through which the material, after being fused, may drain into the tank proper. For the purpose of affording greater rigidity, I have provided, at intervals lengthwise of the pockets, transverse 70 partitions 20-20. The rounded bottom of the trough is enveloped by a jacket 21, which, as will be noted more especially from Fig. III is open at its ends so that air may circulate freely therethrough as suggested by 80 the arrows. The plate 22 by which the jacket is formed is extended somewhat along the sloping sides of the trough so that it may be conveniently attached to the latter by riveting or otherwise. The continuous circulation 85 of air through the jacket 21, it will be seen, serves to prevent burning of that portion of the contents of the trough which is subjected to the greatest heat.

In order to secure the highest possible efficiency, I aim to draw the heat in a general upward direction from the bottom of the fire box along the sides of the trough before being discharged through the flue 7. This desideratum I obtain by providing each of the side walls 1 and 2 near the bottom of the enclosure with a series of inlets 25, and near the top with a series of outlets 26, as a consequence of which, lateral circulation is set up at each side of and throughout the length 90 of the trough.

From the foregoing, it will be readily apparent that a melting kettle constructed in accordance with my invention is highly efficient by reason of uniform distribution of the heating medium to impinge against all portions of the extended surface area of the trough, and moreover, by provision of the 100 105

preheating pockets, the process of melting may be carried on continuously while the trough is at all times accessible from the top so that the contents may be removed therefrom by aid of dippers such as ordinarily used in connection with melting kettles.

If desired, the structure may be provided with wheels or mounted in any approved manner so that it may be readily transferred from place to place.

Having thus described my invention, I claim:

1. A melting kettle comprising an enclosure serviceable as a fire box, and a melting trough suspended within the enclosure, said trough having V shaped cross section with its sides sloping at comparatively steep angles and merging into a rounded bottom the trough being located wholly in said fire box.

2. A melting kettle comprising an enclosure serviceable as a fire box, and a melting trough suspended within the enclosure, said trough being enveloped by an open-ended jacket through which air is free to circulate in order to protect the contents of the trough from direct action of the fire.

3. A melting kettle comprising an enclosure serviceable as a fire box, and a melting trough suspended within the enclosure having V shaped cross section with its sides sloping at comparatively steep angles and merging into a rounded bottom, said trough having also an open-ended jacket enveloping its rounded bottom through which air is free to circulate in order to protect the contents of the trough from direct action of the most intense heat of the fire.

4. A melting kettle comprising an enclosure serviceable as a fire box having near the bottom of one end wall an opening for charging and also for admitting air necessary to support combustion, a flue leading from an opening near the top of the opposite end wall, and a melting trough suspended within and extending wholly into the fire box, and terminating short of the last mentioned end wall of the enclosure to afford a vertical interspace for passage of the products of combustion en route to the flue.

5. A melting kettle comprising an enclosure serviceable as a fire box and having a draft opening and a flue, and a melting trough suspended within said enclosure, the side walls of the latter having near the bottom inlet apertures in addition to the draft opening, and near the top outlet apertures in addition to the flue for the purpose of inducing upward draft and consequent uniform distribution of the heat along the sides and throughout the length of the trough.

6. A melting kettle comprising a fire box, and a trough suspended above the fire box and extending wholly thereinto, said trough having subdivisions or pockets for storage and preheating of the solid material which

is to be melted, said pockets draining through restricted outlets into the trough proper.

7. A melting kettle comprising a fire box, and an elongated trough of V shaped cross section suspended above the fire box, said trough having longitudinally extending subdivisions along opposite sides serviceable as pockets for storage and preheating of the solid material which is to be melted, said subdivisions being set apart by vertical partitions terminating slightly above the sloping sides of the trough to afford restricted outlets through which the material may drain into the trough proper.

8. A melting kettle comprising an enclosure serviceable as a fire box, a trough mounted above the firebox and extending directly thereinto so as to be subject directly to the flame and heat of combustion and having a sloping wall, and means cooperating with said wall to form a retaining pocket in which to receive solid material to be fused, the liquefied material flowing from the pocket to the bottom of the trough.

9. A melting kettle comprising, an enclosure serviceable as a fire box, a trough mounted therein and having a sloping wall, a partition cooperating with the wall to form a retaining compartment, and a series of transverse partitions subdividing the compartment into a number of pockets in which to receive solid material to be fused, the liquefied material flowing from the pockets to the bottom of the trough.

10. A melting kettle comprising an enclosure serviceable as a firebox, a trough, substantially V-shaped in cross section and having converging walls depending directly into the fire box so that both walls are subjected simultaneously to the heat of combustion, a partition along the upper edge of each wall in spaced relation to form retaining compartments in which to receive solid material to be melted, the liquefied material flowing from the compartments to the bottom of the trough.

11. A melting kettle comprising an enclosure serviceable as a fire box, a trough depending into the fire box and having a sloping wall, a retaining means in spaced relation to the wall adjacent the upper portion of the latter to form a retaining pocket in which to receive solid material to be fused, the liquefied material flowing from the pocket to the bottom of the trough for accumulation, and direct exposure to the heat, the wall of the enclosure having openings adjacent its upper portion to create a path for hot gases running in close proximity to the walls of the retaining pocket to promote fusion of the solid material.

12. A melting kettle comprising an enclosure serviceable as a fire box having a draft opening at one end and a flue at the

- other end, forming a direct draft channel, a trough depending into the enclosure and having downwardly converging walls terminating in a rounded bottom extending 5 contiguously to the draft channel, the flue end of the trough being spaced from the adjacent wall of the enclosure to form a draft passage communicating with the firebox and the flue.
- 10 13. A melting kettle comprising an enclosure serviceable as a fire box and having a draft opening and a flue, a V-shaped trough depending into the enclosure with downwardly converging walls, whereby the 15 gases of combustion may flow along the bottom of the trough longitudinally thereof, from opening to flue to heat the trough, opposed side walls of the enclosure facing the trough walls having openings at the lower 20 and upper edges to create a flow of hot gases upward along the trough walls to heat every portion of the latter.
14. A melting kettle comprising an enclosure serviceable as a fire box and having a draft opening at one end and a flue at the other end; a trough depending into the enclosure and having downwardly converging walls terminating in a rounded bottom running endwise between the draft opening and 30 flue, the trough terminating short of the flue end wall of the enclosure to form a draft
- passage communicating with the fire box and flue, a plate covering the bottom of the trough in spaced relation and provided with open ends to permit flow of gases through 35 the space, retaining plates mounted in spaced relation to the upper edge of each trough wall to form retaining compartments for solid material, opposed side walls of the enclosure facing the trough walls having 40 lower and upper openings to create an upward draft to heat every portion of the trough walls.
15. In a melting kettle, a trough to receive melted material, means to retain the 45 solid material to be melted and to permit the material as fast as it is fused to drain into the trough, and a firebox receiving the trough and the retaining means in such a manner that the portion of the trough in 50 which the melted material is collected and the retaining means enclosing the solid material are both subjected simultaneously and directly to the flame and heat of combustion.

In testimony whereof, I have hereunto 55 signed my name at Chicago, Illinois, this 10th day of October, 1921.

CHARLES STEWART BABB.
